UNITED STATES PATENT OFFICE

VERNON H. JONES, OF CHICAGO, ILLINOIS

DISPLAY RACK

Application filed January 6, 1928. Serial No. 244,939.

The invention relates broadly to display racks and has for its primary object the provision of a novel adjustable display rack adapted to be converted into any one of a plurality of different forms for displaying many entirely different forms of merchandise.

Another object of the invention is to provide a new and improved rack that may be so folded and tilted that it will be suitable for holding a hat, such as a fedora, without the usual necessary padding for the crown, and will snugly engage the dent or crease in the crown of the hat.

Another object of the invention is to provide a novel rack that can be folded into a form to hold a plurality of articles at one time and at different levels, for example a plurality of plates or dishes one above the other.

Another object of the invention is to provide a novel rack that can be folded to carry a long support on which silk or other fabric is adapted to be draped so as to be advantageously displayed.

Another object of the invention is to provide a novel rack that is made of wire light of structure, that is easy to manufacture and inexpensive, and that is provided with means for mounting it on any one of a plurality of different sized standards.

Another object of the invention is to provide means for locking the device in any one of its plurality of converted or adjusted forms.

With the foregoing and such other objects in view as will appear as the description proceeds, the invention resides in the combination and arrangement of parts and in the details of construction hereinafter described and claimed, it being understood that changes in the precise embodiment herein described may be made within the scope of what is claimed without departing from the spirit of the invention.

In the accompanying drawing:

Figure 1 is a side elevation of a display stand with a rack embodying the features of my invention.

Figure 2 is a partial plan view taken on line 2-2 of Fig. 1.

Figure 3 is a longitudinal section taken on line 3-3 of Fig. 2.

Figure 4 is a transverse section taken on line 4-4 of Fig. 2.

Figure 5 is a side elevation of the rack adjusted to form two parallel display shelves, one over the other.

Figure 6 is a side elevation of the rack adjusted to display dishes or the like on edge.

Figure 7 is a side elevation of the rack adjusted to hold a display sign or the like in readable position.

Figure 8 is a side elevation of the rack adjusted into a stand for supporting articles of considerable weight.

Figure 9 is a side elevation of the rack adjusted to form a hook and hat rest.

Figure 10 is a side elevation of the rack adjusted to carry a long member for displaying fabric.

Figure 11 is a fragmentary perspective view of a display stand with the rack in collapsible position and with a fedora, indicated in dotted lines, mounted thereon.

Figure 12 is a transverse section taken on line 12-12 of Figure 11.

The rack proper constituting the preferred embodiment of the invention, comprises a center section 13, end wings 14 and 15 pivotally secured to the ends of said section and a universal connection 16 securing said section to a suitable supporting stand 36.

The central section 13 comprises complementary companion side frames 17 and 18, each of which is in the form of a wire loop having a bottom member 19 and an upper arcuate member 21. In the present instance, the members 19 are parallel, and the members 21 are curved apart and away from the member 19. The joined ends of the members 19 and 21 are fashioned to form eyes adapted to receive suitable pintles 25 to which the wings 14 and 15 are also pivotally secured.

Each frame is formed adjoining each end, with an inward kink or notch 22 adapted to provide a rest or seat for certain articles to be displayed. The frames 17 and 18 are in

tegrally joined at their center by a cross member 23 bridging the members 19, and forming part of the connection 16.

The wings 14 and 15 are preferably formed of a piece of wire bent to substantially U-shape, with the closed end of each bent upwardly and with an eye formed in the end of each leg.

The eyes on the wings receive the pintles 25 and preferably those on the wing 14 disposed inside of the eyes on one end of the member 13, and those on the wing 15 are disposed on the outside of the eyes on the other end of said member. Spacers 26 are provided on the pintles 25 between the eyes and a thumb screw 27 is provided on each pintle to frictionally clamp the parts together so as to hold the wings in adjusted position relative to the central section.

The connection 16, see Fig. 4, comprises a socket member 28 adapted to embrace a ball 24 rigid with the cross member 23. In the present instance, the socket member 28 comprises a body part 29 having a stud 31 with a wing nut 32 on the end thereof, and a clamp 30 adapted to be secured thereto by the stud 31 so as to clamp the ball 24. The lower end of this member 28 is adapted to be secured to any suitable support, such as the stand 36, and to this end is tapped as at 33, to receive a ferrule 34 provided to fit over a turned portion 35 of the stand 36. It is to be here noted that a plurality of ferrules of different sizes may be provided so that the rack may be used on a number of differently sized stands.

The rack adjusted, as shown in Fig. 1, is adapted for the displaying of a great many lines of different kinds of merchandise, and particularly for the draping of ladies' dresses, and wearing apparel generally.

The rack adjusted to the position as illustrated in Fig. 5 has the central section 13 tilted obliquely, with the wings 14 and 15 disposed horizontally one above the other, so that small articles may be displayed at different levels.

In Fig. 7, the rack is adjusted so that the central section 13 is reversed through 180° from the position shown in Fig. 5. The wing 15 is extended in continuation of the lower edge of the member 19, of the central section. The wing 14 is bent inwardly so as to form a rest for the article to be displayed thereon, the other end of said article being held against displacement by the bent end of the wing 15.

Fig. 8 shows the rack as displayed in Fig. 7 with the central section disposed horizontally and with the wings 14 and 15 adjusted obliquely upwardly so that their bent ends are located slightly above the crown of the central member. A flat member resting on the arcuate portions; i. e. members 21, of the central section and held under the bent por-

tion of the wings 14 and 15 provides a stand that will support considerable weight.

In Fig. 9, the rack is so positioned as to be adapted to hang articles on the bent portion of the wing 15, and to display another article, such as a straw hat, on the remaining portion. The central section, in this adaptation, is adjusted obliquely upwardly relative to the stand, and the wing 14 is folded between the companion frames.

The display rack, as illustrated in Fig. 6, is shown with its central section disposed horizontal and the wings 14 and 15 disposed upwardly and downwardly respectively, with respect to said sections. In the form as here illustrated, it is obvious that it is adapted to carry china-ware, such as plates or platters on edge, with one plate held in position by the notch 22 and the wing 14, and another plate held by the bent-up portion of the wing 15 and resting against the back of the wing and the end of the central section.

The rack, as illustrated in Fig. 10, shows the central section disposed horizontally and the wing sections 14 and 15 extending obliquely upwardly, and a long member such as a 1" x 4" extending between the two companion frames, and through the wing sections.

The long member is held in position against tilting in either direction by the wings, thus adapting it for displaying silks or fabrics spread out over their full width.

The rack, as illustrated in Figures 11 and 12, shows it in a folded position with the central section tilted upwardly and obliquely outwardly at an angle, with the wing 14 folded between the companion frames, and the wing 15 folded outside the frame. In this form the rack is adapted to support a hat. It will be obvious, from the drawing, that the crease or dent in the crown of the hat will fit between the companion frames, and that the arcuate portion of said frames will hold the hat in the desired tilted position without the usual necessity of padding the inside of the crown of the hat, which is usually necessary in displaying fedoras on racks of known construction, to prevent them from becoming deformed.

Although the preferred embodiment of the improved display rack has been illustrated in the accompanying drawings and described in the foregoing specification, it is to be understood that the invention is capable of embodying certain modifications in detail structure without departing from the spirit of the invention or the scope of the appended claims.

I claim:

1. An article of the class described having, in combination, a central section comprising frames held in spaced relationship, the upper rims of said frames being formed arcuate and having aligning notches formed therein, each adapted to act as a rest for an article to

be displayed thereon, wings pivotally secured to the ends of said section, means on each wing adapted to form a rest for an article and means on said section for securing the same to a support.

5 2. An article of the class described having, in combination, a central section comprising arcuate shaped frames held in spaced relation, wings pivotally secured to the ends of said section, each wing having a portion thereof bent to form a stop adapted to hold an article thereon to be displayed, and means associated with said section arranged for mounting on a stand.

10 3. An article of the class described, having in combination, a central section comprising complemental frames held in spaced relationship, wings pivotally secured to the ends of said section, one wing being mounted for rotation between said complemental frames and the other being mounted for rotation outside of said frames, a supporting stand, and means for adjustably securing said section to said stand.

15 4. An article of the class described, having in combination, a central section comprising companion frames held in spaced relationship and adapted to support a hat or the like, wings pivotally secured to the ends of said section, one wing being mounted for rotation between said companion frames and the other wing being mounted for rotation outside of said frames and a universal connection for securing said section to a support.

20 35 In testimony whereof I affix my signature at 10 South La Salle St., Chicago, Illinois.

VERNON H. JONES.
